US0D1111351S

(12) **United States Design Patent** (10) **Patent No.:** **US D1,111,351 S**
(45) **Date of Patent:** **** Feb. 10, 2026**

(54) **SHOE**

(71) Applicant: **Reebok International Limited**,
Altrincham (GB)

(72) Inventors: **Xiaofan Yu Woodward**, Ashland, MA
(US); **John Greenhalgh**, Foxboro, MA
(US); **Dustin Simone**, Boston, MA
(US); **John J. Januszewski**,
Bellingham, MA (US); **Keith Stern**,
Roslindale, MA (US); **Tom Piacentini**,
Franklin, MA (US); **Kyle Plummer**,
Hampstead, NH (US); **Isaac Toonkel**,
Denver, CO (US); **Mike Andrews**, East
Falmouth, MA (US)

(73) Assignee: **Reebok International Limited**,
Altrincham (GB)

(**) Term: **15 Years**

(21) Appl. No.: **29/859,849**

(22) Filed: **Nov. 14, 2022**

(51) LOC (15) Cl. **02-04**

(52) U.S. Cl.
USPC **D2/956**; D2/947; D2/951; D2/953;
D2/960

(57) **CLAIM**

The ornamental design for a shoe as shown and described.

DESCRIPTION

FIG. 1 is a top front perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
